CHAIR OR THE LIKE

Warren Platner, North Haven, Conn., assignor to Knoll
Associates, Inc., New York, N.Y., a corporation of New York

Filed Aug. 31, 1965, Ser. No. 86,788

Term of patent 14 years

(Cl. D15—1)

FIG. 1 is a front perspective view of a low-back chair embodying the new design.

FIG. 2 is a side perspective view of the low-back chair of FIG. 1.

The side of the chair not shown is a mirror image of the side shown.

I claim:

The ornamental design for a chair or the like, as shown and described.
